DESIGN FOR A FASTENER APPLYING TOOL

Harold W. Kost, Birmingham, Mich., assignor to
Detroit Harvester Company, Detroit, Mich., a
corporation of Michigan

Application May 13, 1943, Serial No. 110,201

Term of patent 7 years

To all whom it may concern:

Be it known that I, Harold W. Kost, a citizen
of the United States and a resident of Birming-
ham, Oakland County, Michigan, have invented
a new, original, and ornamental Design for a
Fastener Applying Tool, of which the following is
a specification, reference being had to the accom-
panying drawing, forming a part thereof.

In the drawing:

Figure 1 is a side elevation of a fastener apply-
ing tool showing my new design;

Figure 2 is a top plan view of the tool shown
in Figure 1; and

Figure 3 is a rear end elevation of the tool
shown in Figure 1.

I claim:

The ornamental design for a fastener applying
tool, as shown.

HAROLD W. KOST.
